UNITED STATES PATENT OFFICE.

GEORGE E. MILLER, OF OAKLAND, CALIFORNIA.

GAS-ENGINE STARTER.

1,034,274.

Specification of Letters Patent.

Patented July 30, 1912.

Application filed November 9, 1911. Serial No. 659,331.

To all whom it may concern:

Be it known that I, GEORGE E. MILLER, a citizen of the United States, residing at Oakland, in the county of Alameda and State of California, have invented new and useful Improvements in Gas-Engine Starters, of which the following is a specification.

This invention relates to starting apparatus for internal combustion engines.

The object of the present invention is to provide a starting apparatus for internal combustion engines, such apparatus involving one or more gas retaining chambers which may be suitably attached to or formed with a portion of the cylinder, or of each of the cylinders of the motor.

It is well known that the combustible gases utilized for the operation of internal combustion engines will retain their inflammable property for a considerable time after generation, and it is the object of the present invention to so arrange a series of receptacles or containers, in which may be accumulated a charge of inflammable or explosive gas derived from the generating system of the motor when the latter is running, and which stored charge of gas may be utilized at a later time for the initial starting of the engine, thereby avoiding "cranking."

The invention consists of the parts and the construction and combination of parts, as hereinafter more fully described and claimed, having reference to the accompanying drawings, in which—

Figure 1 is a side elevation of a four-cylinder motor, showing the apparatus attached. Fig. 2 is a detail view of one of the compression chambers with its valve mechanism. Fig. 3 shows the valve in charging position. Fig. 4 shows the valve in closed position. Fig. 5 is a longitudinal section of the valve.

It is a desideratum to devise and provide a practicable apparatus for the reserve of a charge of compressible gas, which charge may be derived from the engine generator, in the present instance, just before the engine ceases operation and after the sparking system has been rendered inoperative. Ordinarily engines of this type will make a few revolutions after the spark has been cut out and this continued motion of the engine results in the pumping of a pure and unexploded charge of gas into one or more of the

cylinders of the engine. The present invention is designed to reserve a portion of this fresh, unexploded gas which is drawn into the engine by its revolution after the spark has been cut out. To that end I provide one or more chambers, as 2, of suitable proportion, which may be formed with, or connected to, one or more of the cylinders of the engine A.

In the present embodiment of the invention I have shown the chambers 2 as connected to the cylinders of the engine by a valve body 3, in which is movable a valve plug 4 which is provided with a port 5 adapted to be turned into alignment with the central channel 6 of the valve body 3. In the upper end of the valve there is provided an automatically seatable puppet valve 7, which is seated in the present instance by an expansible spring 8.

The valve plug 4 is normally turned to the cut off position by means of the connecting rod 9, which may be connected with each of the levers 10 of the valve plugs. During the running of the motor the connecting rod 9 is shifted to such a position that the valves 4 of each of the compression chambers 2 will be turned to cut off the flow of gas from the engine cylinders into the compression chambers 2.

When the operator desires to stop the engine, the usual process is to cut out the spark, and the momentum of the engine is frequently sufficient to turn over the shaft a number of times. This continued revolution of the shaft after the sparking mechanism is inoperative results in the charging of one or more of the engine cylinders with fresh gas. The momentum of the moving parts of the engine will compress the gas in the cylinder and the operator, when desiring to charge the reservoir chambers 2, shifts the connecting link 9 so as to move the valves 4 to open the channel 5 and permit a portion of the gases to be charged or compressed in the chambers 2. At each impulse or compression of gas the puppet valves 7 will lift to permit the gas to accumulate in its respective chamber 2 and immediately seat, thus holding the charge of gas. The operator will permit the valves 4 to remain in open position for a sufficient length of time to enable the chambers 2 to be charged and will then shift the connecting rod 9 to again close the valves 4. Since each of the storage chambers 2 is now charged with a

volume of pure explosive gas which it is well known may be retained in explosive condition for a considerable length of time, when the operator wishes to start the motor, 5 he shifts the connecting rod 9 to turn the valves 4 so as to carry a cam 11, of which there is one on each valve, into lifting engagement with the stem of the puppet valve 7. This mechanical movement results in 10 the lifting of the puppet valves 7 from their seats and allows the compressed explosive charge in the chambers 2 to escape into the engine cylinders, when the connecting rod 9 may again be shifted to close the valves 4. 15 By then turning on the sparking mechanism, the charge of gas which had been admitted into the engine cylinders, will be exploded, thus energizing the engine.

Having thus described my invention, what 20 I claim and desire to secure by Letters Patent is—

1. The combination with an internal combustion motor, of a reservoir chamber, connections between said chamber and a combustion cylinder of the motor, an automatic valve interposed between said chamber and said cylinder, and a valve operable to open communication between the cylinder and the 25

reservoir chamber to allow the latter to be charged, said last named valve having a cam 30 surface and the automatic valve having a part disposed in the range of action of said cam surface and adapted to be lifted thereby.

2. The combination with an internal combustion motor, of a reservoir chamber, connections between said chamber and a combustion cylinder of the motor, an automatic valve interposed between said chamber and said cylinder, a valve operable to open communication between the cylinder and the reservoir chamber to allow the latter to be charged, and means for opening the automatic valve to allow the compressed gas to escape into the cylinder of the motor, said 40 means including a rotatable cam on the second named valve, and said automatic valve having a stem to be engaged and lifted by said cam.

In testimony whereof I have hereunto set 50 my hand in the presence of two subscribing witnesses.

GEORGE E. MILLER.
